UNITED STATES PATENT OFFICE.

ROSARIO GENOVESE, OF NEW YORK, N. Y.

TOY FLYING MACHINE.

Specification of Letters Patent. Patented May 9, 1922.

1,415,833.

Application filed March 30, 1921. Serial No. 456,852.

To all whom it may concern:

Be it known that ROSARIO GENOVESE, a citizen of the United States, and residing at New York, in the county of Bronx and State of New York, have invented certain new and useful Improvements in Toy Flying Machines, of which the following is a specification, such as will enable those skilled in the art to which it appertains to make and use 10 the same.

This invention relates to toy flying machines and particularly to devices of this class of the monoplane type, and the object thereof is to provide a device of this class 15 the frame-work or body portion of which is composed entirely of reed material, whereby said device is made of the least possible weight; a further object being to provide a device of the class specified which is provided 20 with a propeller driven by spring power mechanism, and which will raise itself from the ground or a floor on which it is placed and which will fly like operative machines of the class referred to for a certain distance; 25 and with these and other objects in view the invention consists in a toy flying machine constructed and operating as hereinafter described and claimed.

The invention is fully disclosed in the following specification, of which the accompanying drawing forms a part and in which the separate parts of my improvement are designated by suitable reference characters in each of the views, and in which:—

35 Fig. 1 is a plan view of my improved toy flying machine, one end portion of the plane being broken away;

Fig. 2 a side view thereof with parts of the construction broken away;

40 Fig. 3 a front end view of the device as shown in Fig. 1;

Fig. 4 a section on the line 4—4 of Fig. 2;

Fig. 5 a partial, sectional view on the line 5—5 of Fig. 2;

45 Fig. 6 a detailed view showing the construction of the frame of the plane; and

Fig. 7 a partial section on the line 7—7 of Fig. 2.

In the practice of my invention the entire 50 body or frame-work of the machine is composed of reed material, and comprises horizontally or longitudinally arranged top reed members α and bottom reed members α^2 , together with vertically arranged front reed members α^3 and rear reed members α^4 and other side reed members α^5 , which are curved

as shown in Fig. 5, and connected with the top reed members α and the bottom reed members α^2 as shown at α^6 and α^7 , the connections at α^6 being made by inter-twining or twisting the parts together and those at α^7 being made by bands in the form of construction shown; and all the said reed members where they engage one another or are connected with one another, may be so connected by bands as shown at α^8 or by means of wire ties as shown at α^9 . The reed members α and α^5 project forwardly of the body of the machine and are secured to a front plate b , and the reed members α^2 and α^3 are 65 connected below the body of the machine as shown at b^2 , and at each side of the machine these reed members are formed into downwardly directed loops b^3 in which are mounted transverse axles b^4 provided with 70 wheels b^5 , on which the front of the body portion of the machine rests.

The rear end portions of the bottom reed members α^2 are formed into downwardly directed loops b^6 which normally support the 80 rear end portion of the machine, and the front parts of the loops b^6 are extended upwardly above the bottom reed members α^2 and connected with the rear end portions of the reed members α and α^5 and with a transverse block c in which is mounted a vertical reed member c^2 with which is connected a 85 backwardly directed wing member c^3 which serves as a rudder, and the horizontally arranged reed frame members α^5 are extended 90 beyond the block c , and formed into approximately elliptical loops c^4 having a continuous fabric covering c^5 , and these parts form a supplemental plane which also aids the rudder c^3 in guiding the machine and keeping 95 it in proper position.

Mounted transversely in the central body portion of the machine is a transverse loop shaped frame member d composed of reed material and to which is secured a transverse 100 plate d^2 as shown in Fig. 4, this connection being made by opposite side tongues d^3 on the plate d^2 , which are folded around the side parts of the transverse frame member d .

Mounted in front of the plate d^2 is a spring 105 power casing e having a back plate e^2 which is secured to the plate d^2 by bolts or screws e^3 , and mounted in the front of the body portion of the machine and centrally thereof is a horizontal or approximately horizontal 110 propeller shaft f the front end of which extends forwardly through the plate b , and is

provided with a propeller f^2 and the rear end of the propeller shaft extends through the casing e and mounted thereon, within said casing, is a pinion gear f^3 which is adapted to operate in connection with a large gear wheel g mounted on a shaft g^2 mounted in the casing e and to which is secured one end of a spiral spring g^3 , the other end of which is secured to one side of the casing e 10 as shown at g^4 , or in any other desired manner.

The pinion gear f^3 is provided with radial pins or fingers f^4 and mounted thereover on a pivot pin f^5 is a crank arm f^6 , the head 15 portion of which is provided with a projecting finger f^7 provided with a transverse nose or stop f^8 adapted to operate in connection with the radial pins or fingers f^4 on the gear f^3 .

20 Mounted on the front side of the propeller and centrally thereof is a plate h and pivoted to said plate is a double ended pawl h^2 which operates in connection with a ratchet h^3 secured to the propeller shaft f outwardly 25 of the plate h .

The back of the casing e is provided with a keyhole i in which a key may be inserted to turn the propeller shaft and wind up the spring g^3 , or said propeller shaft may be 30 turned by means of the propeller f^2 to wind up said spring and said propeller shaft is also provided within the frame or body portion of the device with the usual governor i^2 which may be mounted thereon or connected therewith in any desired manner.

35 Mounted transversely of and on the body portion of the machine is the main plane j which comprises a frame-work j^2 of reed material provided with a covering j^3 of fabric, 40 and the frame j^2 is composed of separate reeds j^4 formed into central loops j^5 and into parallel projecting side loops j^6 , parts of which are broken away in Fig. 6, and the center loops j^5 are connected as shown at j^7 45 by suitable bands or ties, and mounted in the central part of said frame-work is a vertical pin j^8 which passes centrally through the main plane, and said main plane is secured into position by a nut and washer j^9 , and said main plane is provided centrally of 50 its rear edge with an inwardly directed recess k through which the crank arm f^6 passes.

55 With the construction herein described the propeller and propeller shaft may be manipulated to wind up the spring g^3 , as hereinbefore stated, or the propeller shaft may be turned for this purpose by means of a key inserted into the casing e at i , and the 60 crank arm f^6 may be operated to hold the spring g^3 in a wound up condition until it is desired to release said spring and permit it to operate the propeller shaft and propeller, and it will be understood that the 65 spring g^3 may be of any desired length or

power and when said spring is fully wound up the machine may be placed on a floor or other support and the crank arm f^6 disengaged from the gear f^3 and this will set the spring g^3 in operation and the operation of 70 said spring will turn the propeller shaft and propeller and the machine will rise from the ground and fly in the manner of operative devices of this class, the height to which the machine rises and the length of the flight 75 thereof depending on the length and power of the spring g^3 .

My invention is not limited to any particular method of forming the main body or frame-work of the machine from reeds or 80 reed material as herein described, or any particular arrangement of said reeds or reed material or to any particular means for connecting the parts thereof. I prefer to make the frame-work or body portion of 85 the machine of reeds or reed material in such manner as to give said frame-work or body portion the least possible weight, and while I have shown certain other details of construction including the operative parts of 90 the device and means for supporting the same, my invention is not limited to these exact details and changes therein and modifications thereof may be made within the scope of the appended claims without departing from the spirit of my invention or 95 sacrificing its advantages.

It will also be understood that my invention is not limited to the gearing herein described between the propeller shaft and the 100 spring power mechanism, and any suitable gearing may be provided whereby the spring may be wound up by the propeller shaft and driven by the spring.

Having fully described my invention, that 105 which I claim as new and desire to secure by Letters Patent, is:—

1. In a toy flying machine of the class described, a body or frame-work composed entirely of reeds or reed material, a spring 110 power casing mounted centrally and transversely of said frame work a propeller shaft mounted in the front portion of the body or frame-work and projecting forwardly thereof and provided with a propeller, said propeller shaft being also provided within said casing with a gear, a lock device operating in connection with said gear, a spring shaft mounted below said gear and provided with a large gear which operates in connection 115 therewith, a spiral spring mounted on said spring shaft and one end of which is connected therewith and the other end with said casing, a ratchet wheel mounted on the propeller and a pawl operating in connection therewith whereby the spring may be wound up by means of the propeller and propeller shaft, and means whereby said spring may also be wound up by a key inserted 125 through the back of said casing.

2. In a toy flying machine of the class described, a body or framework, a spring power casing mounted centrally and transversely of said body or framework, a propeller shaft mounted in the front portion of the body or framework and projecting forwardly thereof and provided with a propeller, said propeller shaft being also provided within said casing with a gear, a lock device operating in connection with said gear, a spring shaft mounted below said gear and provided with a large gear which operates in connection therewith, a spiral spring mounted on said spring shaft and one end of which is connected therewith and the other end with said casing, a ratchet wheel mounted on the propeller and a pawl operating in connection therewith whereby the spring may be wound up by means of the propeller and propeller shaft, and means whereby said spring may also be wound up by a key inserted through the back of said casing.
3. In a toy flying machine of the class described, a spring power casing mounted centrally and transversely in the body or frame-
- work of the machine, a propeller shaft mounted in the front part of the body or framework and one end of which projects forwardly thereof and the other end of which extends into said casing and is provided with a gear, a lock device operating in connection with said gear, a spring shaft mounted below the gear on the propeller shaft and provided with a large gear operating in connection therewith, and a spiral spring mounted on said spring shaft and one end of which is connected therewith and the other with the casing, said propeller shaft being provided at its front end with a propeller, and means whereby said spring may be wound up by the propeller shaft or by a key inserted through the back of said casing.
- In testimony that I claim the foregoing as my invention I have signed my name in presence of the subscribing witnesses this 28th day of March, 1921.

ROSARIO GENOVESE.
